REVERSING-GEAR FOR MOTORS WITH VALVE-GEAR WORKED BY CAMS AND LEVERS.

1,341,368.

Specification of Letters Patent.

Patented May 25, 1920.

Application filed June 12, 1918. Serial No. 239,648.

To all whom it may concern:

Be it known that I, RENÉ GUYOT-SIONNEST, of 95 Rue Jouffroy, at Paris, Department of the Seine, France, citizen of the 5 French Republic, have invented certain new and useful Improvements in Reversing-Gear for Motors with Valve-Gear Worked by Cams and Levers; and I do hereby declare the following to be a full, clear, and exact 10 description of the invention, such as will enable others skilled in the art to which it appertains to make and use the same.

The object of this invention is to effect 15 improvements in devices which permit of direct modification of the direction of motion of motors and particularly of explosion or internal combustion motors in which the distribution is effected by cams or eccentrics and levers. 20 The majority of devices in use consist either in longitudinally moving a single shaft carrying forward and backward gear cams, or in providing two shafts carrying respectively the two sets of cams and adapted to replace each other. The first of these 25 systems has the disadvantage of necessitating before the shaft is moved the lifting of the rollers which oppose this movement and the second necessitates a very delicate adjustment and the presence of heavy parts which take up much space.

The improved arrangement, the "Lugt" 30 system which forms the subject matter of this invention, is free from these disadvantages. This arrangement is characterized by the mounting of the two sets of cams, intended for forward and backward gear, upon a single shaft which neither moves longitudinally nor laterally, the intermediate 35 levers oscillating about their axis of oscillation which are not parallel to the axis of the cam shaft and the one or the other of the sets of cams are set in operation by a movement of their axis of oscillation.

In the accompanying drawing is represented by way of example the application of the subject matter of the invention to a Diesel motor.

Figure 1 shows in plan (certain parts being shown in section for greater clearness) the parts for operating the valve gear of a Diesel motor.

Figs. 2 and 3 show respectively in eleva-

tion the different levers acting on the parts of the valve gear.

55

Fig. 4 is a detailed view, showing the mechanism for operating the starting valve.

The constructional form represented shows the application of the improved arrangement to the operation of a four stroke cycle 60 Diesel motor.

The operation of the suction and exhaust valves is effected by means of two levers 3, 3 of identical construction and operation. Only one of them will therefore be described.

1, (see Fig. 2) is the rod of one of the suction or exhaust valves supposed to be vertical, 2 is the cam shaft, the axis of which is horizontal and 3 is the operating lever. This lever turns on an eccentric 4 which is 70 keyed on a shaft 5; the axis of the eccentric 4 is not parallel to the axis of the shaft 5 and may or may not meet it. The inclination of the axis has been slightly exaggerated in the drawings for the sake of greater 75 clearness. One end of the lever 3 bears by a screw 6 on the rod 1, the contact being maintained by a spring 7; the other end carries a roller 8 which is worked by a cam 9 mounted on the cam shaft 2 and which 80 represents the forward gear cam.

To change the direction of movement, the shaft 5 is made to rotate half a revolution, while causing it to advance a certain amount by the aid of the arrangement shown in 85 Fig. 1, and which comprises an operating shaft 33 at right angles to the shaft 5. The shaft 33 receives its motion from a train of gears suitably calculated so that the force to be employed shall not be too great and 90 carries two cranks 34 and a toothed conical wheel 35. Upon the shaft 5 is mounted a collar 36 having two trunnions 36' which are connected to the tangs of the cranks 34 by connecting rods 37. A conical wheel 38 95 is mounted upon the shaft 5 which it rotates by a key 39 and is yet able to slide longitudinally thereon. When the shaft 33 is caused to make half a revolution, the shaft 5 also makes half a revolution and moves 100 forward under the action of the connecting rods 37. The lever 3 then assumes the position 3' indicated by dotted lines. The screw 10 takes the place of the screw 6 and bears on the valve rod 1, while the roller 8 is 105 worked by the cam 11 which is the backward

gear cam. During this movement the center of the eccentric 4 about which the lever 3 turns is raised, as the end of the lever placed beside the valve always tends to descend by the action of the spring 7, the other end, and consequently the roller, have followed the rising movement. The movement of translation has therefore been able to produce itself whatever be the position 10 of the cam shaft 2, without the roller 8 touching the cams. It is only in the latter part of the movement that the roller comes to rest on the new cam.

Fig. 3 shows in elevation the lever used 15 for working the fuel needle of the Diesel motor; 12 is the valve rod supposed to be vertical and opening upward as in the majority of Diesel motors; 13 and 14 are the forward and backward gear cams keyed on 20 the common shaft 2 for all the cams. 15 is the operating lever carrying at one end the roller 16 worked by the forward and backward gear cams and at the other end the two regulating screws 17 and 18. 15' is 25 the position of this cam lever (indicated by dotted lines) in the case of backward gear. 19 is an intermediate piece turning about the shaft 20 and adapted to receive the downward movement of the screws 17 and 30 18, and transmit it to the rod 12 transforming it into an upward movement. 21 represents the eccentric keyed on the shaft 5, oblique with respect to this shaft, mounted in the same way as the eccentric 4, and about 35 which turns the lever 15. The movement is effected as previously described, the roller rises, moves and after having quitted the forward gear cam places itself on the backward gear cam; the screw 18 takes the place 40 of the screw 17, the positions of these two screws being chosen in such a way that the height of elevation of the valve is the same in both forward and backward gears.

Figs. 1 and 4 show finally the method of 45 operation which may be used for the starting valve. 22 is the rod of the valve and 23 is a cam keyed on the shaft 5 the object of which will be described hereafter. A lever 24 rotates freely about the shaft 5 but 50 is carried along in the movement of translation of this shaft in such a way that the roller 25 fixed to its end is brought successively opposite the cams 26 and 27 for forward and backward gear. A spring 28 tends to keep the roller raised. Below the 55 lever 24 is hung by a rod 29 the double lever 30 which bears on the other hand on the valve rod 22. At the center of this lever 30 is a rotating shaft 31 which is adapted to 60 bear upon the projecting parts 32 and 32' of the cam 23. This shaft 31 serves as an axis of oscillation to the lever 30. This shaft 31 is not parallel to the axis of the cam shaft and is capable of taking up two different positions as hereinbefore stated.

As long as the shaft 31 does not touch the projecting parts, all the movable part of the system is kept raised by the spring 28 and the roller 25 is not touched by the starting cams. The valve consequently remains at 70 rest. When the shaft 5 in its rotation assumes such a position that the shaft 31 touches one of the projecting parts 32 and 32' the roller 25 is drawn down onto its cam and the valve obeys this latter. This corresponds to the starting position which is represented in Fig. 4. The keying of the cam 23 on the shaft 5 is such that this starting position is obtained at each change of gear a little before the complete movement 80 of the shaft 5 is accomplished. At this moment, the axis of rotation of the operating lever 15 of the fuel needle has not yet taken up its fuel position and consequent upon the low height of the corresponding cam the 85 valve remains at rest and the introduction of the fuel into the cylinder is able to take place. On the other hand by virtue of large dimensions of the suction and exhaust cams and although the axis of rotation of the lever 90 31' has not yet attained its running position, these latter valves may be raised by their cams at points on the stroke of the piston which differ but little from those fixed by the adjustment diagram of the 95 valve gear. The working for passing from forward to backward gear or vice versa consists therefore simply in causing the operating shaft 33 to rotate through an angle slightly less than half a revolution, so as to 100 place the motor in the starting position. As soon as the motor has picked up its speed, it will suffice to slightly turn the shaft 33 so as to cause it to finish its rotation of half a revolution; the motor will therefore 105 be in its starting position.

If the number of cylinders is at least six and if the starting cams are of suitable size the motor will start in any position whatsoever of the crank shaft. In any case for 110 motors with three or four cylinders, it will often be necessary to turn the motor to put it into a position for starting.

By means of a slight modification, motors having starting valves operated as hereinbefore described may easily be brought into a starting position without being turned by hand and without any special apparatus, by the simple introduction of compressed air into one of the cylinders. 115 120

When the motor is stopped in a position in which direct starting is impossible, one of the pistons is always on the suction period. It suffices to keep the suction valves and the exhaust valves closed and to admit 125 air under pressure above this piston to bring it to its lowest dead point. In this new position of the motor one piston is located in such a position that starting is now possible. To this end, the disks 23 (see 130

Fig. 4) are each provided with a complementary projecting part 40 which is adapted to touch the shaft 31 and which is placed at such a point that when this contact takes place the shaft 5 has passed over about half its movement of translation, the roller 25 being against the cams 26 and 27 on the other hand, a special cam placed on the cam shaft between the cams 26 and 27 is so shaped that its projecting parts are opposite the roller 25 when the corresponding cylinder is in a position which corresponds to the suction period.

It will suffice therefore to turn the shaft 5 by hand, the compressed air cock being opened previously; if one of the cylinders is in the desired position, the projecting part 40 which corresponds will touch the shaft 31 at the same time as the roller 25 will be opposite a projecting part of the intermediate cam 41; the starting valve will thus be raised, the air introduced into the cylinder and the motor will commence to turn and be brought into a suitable position for starting. The arrangement described avoids all false working and the air cannot be introduced into a cylinder if this latter is not in the desired position. Before starting the cylinder being thus filled with air under pressure must be emptied of this air; this can be effected by a special valve also worked by the shaft 5 or by any other means.

The arrangements above described are of great simplicity of construction and operation, and can be applied without important modification to all types of motors.

Claims:

1. The combination with a valve, of a shaft having a pair of cams thereon, an os-

cillatory lever, one end of which lever engages the valve and the other end of which is adapted to engage either of the cams, the axis of oscillation of the lever being disposed obliquely to the axis of the shaft, 45 and means for reversing the angularity of the lever to shift the cam engaging end thereof from one to the other of the cams.

2. The combination with a valve, of a shaft having rotative movement only, a pair 50 of cams mounted on said shaft, a lever supporting shaft, a lever mounted on said last mentioned shaft, one end of the lever being adapted to engage the valve and the other end to engage either of the cams, the axis 55 of oscillation of the lever being oblique to the axis of the last mentioned shaft, and means for reversing the angularity of the lever, so that the cam engaging end of the lever is shifted from one to the other of the 60 cams.

3. The combination with a valve, of a shaft having a pair of cams thereon, a lever supporting shaft mounted for rotative and longitudinal movements, an eccentric secured to said shaft, a lever mounted on said eccentric as a bearing, said shaft passing through said eccentric obliquely to the axis of oscillation of the lever, and means for rotating and longitudinally advancing 70 the lever supporting shaft to shift the cam engaging end of the lever from one to the other of the cams.

In testimony whereof I affix my signature in presence of two witnesses.

RENÉ GUYOT-SIONNEST.
